UNITED STATES PATENT OFFICE.

CHARLES TRUESDALE, OF CINCINNATI, OHIO.

MOLDER'S LADLE OR CRUCIBLE.

SPECIFICATION forming part of Letters Patent No. 402,871, dated May 7, 1889.

Application filed April 2, 1889. Serial No. 305,664. (No model.)

To all whom it may concern:

Be it known that I, CHARLES TRUESDALE, a citizen of the United States, residing at Cincinnati, in the county of Hamilton and State of Ohio, have invented certain new and useful Improvements in Molders' Ladles or Crucibles; and I do declare the following to be a full, clear, and exact description of the invention, reference being had to the accompanying drawings, which form a part of this specification.

Molders' ladles as ordinarily made are coated internally with a lining of loam or other suitable material, which is applied in a plastic condition, after which act the ladles are dried in an oven for the purpose of evaporating any water or moisture that may be contained in said lining; but the temperature of the oven is insufficient to expel all the moisture, and consequently when the ladle is first filled with molten metal the intense heat of the same causes the lining to give off a gas or vapor that can escape only by passing through the metal. This escape of gas causes the metal to "boil," as it is technically called by foundry-men, thereby rendering it unfit for use and compelling it to be poured out on the ground, so as to enable the ladle to be filled a second time before its contents can be run into a mold.

To prevent this waste of time, labor, and metal, I slot the sides of the ladle, which simple expedient allows the gas or vapor to escape freely, and thereby prevents the objectionable "boiling." The slots are preferably made in a ladle having an inwardly-converging top, which convergence prevents the lining working up by the contraction of the metal while waiting for the ladle to be refilled. Furthermore, it is preferred to locate an annular groove within the ladle and above said slots, which groove coacts with the converging top in securing the lining in place, as hereinafter more fully described.

In the annexed drawings, Figure 1 is a sectional side elevation of my improved ladle. Fig. 2 is a horizontal section thereof, said section being taken at the line α α of the preceding illustration and the lining being

applied to the ladle. Fig. 3 is a greatly-enlarged vertical section of a portion of the lined ladle.

The ladle proper, A, is a casting of any suitable size and shape, and has an annular flange or rim, B, from which flange slots C run down almost to the bottom of said ladle.

These side slots may be of such size and shape as circumstances suggest, and a sufficient number of them must be provided to allow a free escape of gas from the lining.

E is the upper or unslotted portion of the ladle, which portion converges inwardly at the top and has at the bottom an internal annular groove, F.

G is the loam or other lining of the ladle or crucible, which lining may be applied by hand in the usual way, the water contained in it being evaporated by placing the ladle in an oven; but the temperature of an oven is insufficient to completely evaporate all the moisture from the lining, and therefore when molten metal is poured into the ladle the intense heat of the metal causes a sudden generation of gas and other vapors, which vapors escape freely through the side slots, C. Consequently there is no boiling of the metal, and on this account it is in a proper condition to be poured directly into the mold or flask. After pouring out the metal and before the ladle is again filled it cools to a certain extent, and the consequent contraction tends to loosen the filling, G, and cause it to work up, which loosening is counteracted by the inwardly-converging top E, that holds said lining in place. This upward shifting of the lining is further guarded against by anchoring it within the annular groove F as seen in Fig. 4. Finally, by giving the ladle A an outward flare or curve from the lower ends of slots C up to the marginal rim B the pattern can be readily drawn off from the "cores" that form said slots.

I claim as my invention—

1. As a new article of manufacture, a molder's ladle or crucible having its sides pierced with a series of slots, for the purpose specified.

2. A molder's ladle or crucible consisting

of an upper portion having an inwardly-converging top and a lower portion having slotted sides, substantially as herein described.

5 3. A molder's ladle or crucible having an internal annular groove, an inwardly-converging top, and slotted sides, substantially as herein described.

In testimony whereof I affix my signature in presence of two witnesses.

CHARLES TRUESDALE.
